UNITED STATES PATENT OFFICE.

STERLING ELLIOTT, OF NEWTON, MASSACHUSETTS.

GLUING-MACHINE FOR STENCIL-FRAMES.

1,210,442.

Specification of Letters Patent. Patented Jan. 2, 1917.

Application filed January 15, 1916. Serial No. 72,343.

To all whom it may concern:

Be it known that I, STERLING ELLIOTT, a citizen of the United States, residing at Newton, in the county of Middlesex and 5 State of Massachusetts, have invented an Improvement in Gluing-Machines for Stencil-Frames, of which the following is a specification.

This invention relates to machines for 10 sizing the frames of stencil-blanks, and is particularly adapted for the sizing of the edge frames, and supporting pieces of the stencils or address-plates of the type disclosed in my Patent #1,068,578.

15 One of the principal objects of the invention is to provide a machine by which the stencil-frames are fed from a supply-holder into a gluing-tank and are then conveyed from the gluing-tank to conveying-means, whereon they are allowed to dry and by which they are delivered to stacking-means by which they are stacked in edge 20 wise position in a suitable horizontal receiver.

25 Another important object of the invention is to provide two independent but complementary belts for conveying the stencil-frames from the gluing-tank to the stacking-means, the two belts being so arranged 30 that one face of the stencil-frame is exposed to the atmosphere while on one belt, and the other face exposed to the atmosphere while on the other belt, the blanks being turned over in passing from the one belt 35 to the other.

Another object is the provision at the entrance to the gluing-tank of a pair of accelerating rolls which are adapted to draw each stencil-frame engaged by it away from 40 the following stencil-frames, so that each stencil-frame will, as it enters the gluing-tank, be momentarily spaced from the other frames, thus to assist in feeding the stencil-frames along and to prevent said frames 45 from crowding or overlapping, and thereby becoming wedged in the guide-way along which they are moved.

A further object is to provide an ejecting 50 means by which movement of each stencil-frame, as it is drawn from the gluing tank, is accelerated, and thereby quickly drawn away from the following stencil-frames so that the frames will not be congested or crowded in the track at such points, and 55 thereby injured.

A further object is to provide for mov-

ing the conveying means for the stencil-frames faster than the speed of delivery of the stencil-frames thereto, so that the stencil-frames will be sufficiently spaced from 60 each other upon the conveying-means to admit of thorough drying of the edges of the frame.

A further object is the provision of means to facilitate the removal of the stencil-frames from the bottom of the pile without 65 injury thereto, or to an adjacent frame, each means operating to move the frames in a curvilinear direction while removing them from the bottom of the pile thereby to turn 70 then in a horizontal plane with respect to the frames above them.

Figure 1 is a side elevation of one end-portion of a sizing-machine for stencil-frames embodying this invention. Fig. 2 75 is a side elevation of the middle portion of said machine. Fig. 3 is a longitudinal vertical section of the other end-portion of said machine. Fig. 4 is a horizontal section of the machine shown in Fig. 1, taken on the 80 dotted line 4—4. Fig. 5 is an enlarged detail view of the track along which the stencil-frames or blanks are fed from the holder through the gluing-tank and to the conveying-means. Fig. 6 is an enlarged top 85 plan view of the feeding-mechanism by which the blanks are fed through the track, the ejector arm being shown in retracted position. Fig. 7 is a top plan view of a portion of the feeding-mechanism, with the 90 ejector arm in projected position. Fig. 8 is a detail section taken longitudinally through the exit end of the gluing-tank. Fig. 9 is a top plan view of the stacking apparatus, and receiver. Fig. 10 is a section on the line 95 10—10 of Fig. 9. Fig. 11 is a section on the line 11—11 of Fig. 9. Fig. 12 is a section on the line 12—12 of Fig. 9. Fig. 13 is a section on the line 13—13 of Fig. 9.

As here shown the frame 10, supports the 100 glue-tank 11. Said frame 10 may be of any suitable construction and has parallel transverse beams or bars 14 upon which the terminals of a rectangular reinforcing frame 15 of the tank 11 are supported. The tank 105 11 is preferably of sheet metal and has a curved bottom wall 16, and parallel segmental side walls 17. The upper edges of the side walls and bottom wall are turned over the frame 15, as at 18, Fig. 8, to secure 110 the tank in said frame. Thus the tank may be removed from its supporting-frame 10,

by lifting the frame 15 from these supports 14, for cleaning or other purposes. A pump 19 is provided in connection with the tank. This tank is adapted to contain glue, shell-lac, or any other equivalent cementitious substance, which is to be employed in sizing the stencil-frames, and is herein referred to as a gluing tank.

The supply of stencil-frames, which are to be glued, are arranged in a pile in a suitable holder herein shown as comprising a base-plate 20, vertical channel-shaped guiding-members 21 mounted thereon, and a vertical plate or bar 22, see Figs. 1 and 5. 10 The stencil-frames are fed from this holder by feeding-mechanism which successively removes them from the bottom of the pile. The feeding-mechanism here shown is of novel construction, and comprises an ejector arm 25, secured to the upper end of a shaft 26, and arranged for oscillation in a horizontal plane, over the upper face of a table 27, and across the bottom face of the base plate 20, which is mounted on said table (see Fig. 5).

An arcuate guide-passage 28 (see Figs. 6 and 7) is formed in the upper face of the table 27, which extends beneath the opening in the base-plate 20, through which the stencil-frames pass, said passage being thus adapted to receive the lowermost stencil-frame of the pile. The ejector arm has its free end-portion 29, arranged to move lengthwise of said passage 28, and said end-portion is formed with a tongue 30, which is extended forward, and also offset downwardly with respect to the arm, thereby to form an abrupt shoulder or engaging-portion at the junction of the tongue and arm. 30 The guide-passage 28 has an arcuate groove in its bottom, shaped to correspond with and permit unobstructed movement of said tongue 30. As shown in Figs. 4 to 6, the ejector arm has a backward throw sufficient 35 to enable its shoulder to pass the opening in the base-plate, so that the lowermost stencil-frame will rest on the tongue, and has a forward throw sufficient for its shoulder to engage the rear edge of said lowermost 40 stencil-frame and move said frame forward a distance sufficient to cause its front end to be engaged by a pair of feeding-rolls. Thus as the ejector arm is oscillated the stencil-frames are successively removed from the 45 bottom of the pile. By reason of the guide-passage being arcuate and the ejector arm arranged to oscillate on an axis coincident with the center of the arc of said passage, and the holder for the stencil-frames being 50 arranged in a plane substantially tangential to said arc, the lowermost stencil-frame will be removed from the bottom of the pile in a curvilinear direction corresponding to said arc, instead of being moved straight-away, 55 with the result that it is turned in a hori-

zontal plane while it is being so moved and there is less liability of the inner edges of the stencil-frames engaging each other, and thus obstructing sliding movement of the lowermost frame.

The shaft 26 is turned to oscillate the ejector arm by means of a shaft 33, having a terminal gear 34 driven from a pinion 35, on a stub shaft 36, which is directly connected to the motor or other power source 75 through a belt 37 and belt pulley 38. The shaft 33 extends transversely and is journaled in parallel longitudinal supporting bars 39, which are suitably connected to the vertical bars 40 of a frame which supports 80 the feeding-mechanism, see Fig. 1. To oscillate the shaft 26, a pair of meshing bevel pinions 42, 43, a crank 44, and a pitman 45 are employed. Pinion 42 is secured to shaft 33, and pitman 45 is eccentrically connected 85 to a disk upon the upper face of pinion 43. The crank 44 is secured to the shaft 26. The pitman 45 and crank 44 are adjustably connected so that the throw of the ejector arm may be adjusted.

The rotation of shaft 33 will be communicated to shaft 26 through the pitman 45 to oscillate the ejector arm 25, and thereby effect an intermittent discharge of the stencil-frames from the holder. The stencil-frames thus discharged from the holder are delivered to a track 13, the entrance of which is arranged close to the discharge orifice of the holder. The track 13 comprises a pair of longitudinally curved bars connected 100 by transverse braces 23, the upper ends of which bars are secured to the top of the table 27, see Fig. 5, and the remaining portions being secured to the frame at several points, whereby they are held in fixed relation. This track extends downward into and out of the tank, a portion thereof being arranged below the level of the glue contained in the tank and is employed to support and guide the stencil-frames while they 105 are being moved along from the holder into and out of the tank, the frames being submerged while in transit. The inner or adjacent edges of said bars are grooved longitudinally, see Fig. 4, and said grooves are 110 arranged in continuation of the guide-passage in the table, so that the stencil-frames, upon leaving said guide-passage, will enter the grooved edges of the curved bars and will be supported and guided by them.

As the stencil-frames pass to the track they are engaged by a pair of feeding rolls 46, 47, see Fig. 5, and thereby positively moved along the grooves of the track, each frame abutting against the frame ahead of 115 it. These feeding-rolls are arranged at right angles to the curved bars forming the track, and therefore, first engage a corner of a stencil-frame which is projected forward from the holder by the ejecting arm, 120

and as said positively moved stencil-frame engages the grooves in the bars, and the bars are spaced apart a distance approximately equal to the width of a stencil-frame, said 5 stencil-frame will be turned to a position in parallel relation with the track. The walls of the grooves of the bars forming the track being longitudinally curved, offer a certain 10 resistance to the flat stencil-frames, and consequently while the stencil-frames may be 15 moved along the track by the feeding rolls 46 and 47, each frame engaging the frame ahead of it, they will not fall by gravity. As here shown the rolls 46 and 47 each comprise (see Fig. 6) disks which are secured 20 to shafts 50 and 51, and maintained in spaced relation by hubs or collars 52. Herein the shafts 50, 51, are connected by meshing pinions 53, 54, and are driven by a chain 55, which passes over sprocket-wheels 56 and 25 57, arranged respectively on shafts 50 and 51.

While passing along the track the stencil-frames abut together and as the track is 25 very long and is curved longitudinally there is danger of the frames overlapping and becoming wedged in the grooves of the track, and to obviate this tendency another pair of feeding-rolls 58, 59, is employed, which 30 rolls are herein located some distance in advance of the feeding-rolls 46, 47, being here shown as located just before the track enters the tank, and said additional feeding-rolls serve to engage the stencil frames presented to them, and to independently feed 35 them along the track. The rolls 58 and 59 are here shown as of greater diameter than the rolls 46 and 47, and are, or may be, driven at the same rate of speed, so that the 40 rate of speed of each stencil-frame which they engage is, therefore, suddenly increased, and thereby moved away from the following stencil-frames, but into abutting relation with the frames ahead of it. Herein 45 the rolls 58 and 59 are solid and are mounted upon shafts 60 and 61, journaled in the bars 39, and connected at one end by meshing pinions 62, 63. The shaft 61 has a sprocket-wheel 64, and is driven by a chain 50 65, which passes over said sprocket-wheel and over a sprocket-wheel 66 on shaft 50.

As the stencil-frames emerge from the track at the exit end of the tank they are 55 engaged by the accelerating and ejecting rolls 67 and 68, which rolls also serve to squeeze the frames and remove the surplus glue. The roll 67 is mounted on shaft 33, and the roll 68 is mounted on a parallel 60 shaft 69, said shafts being connected by meshing pinions 70, 71, see Fig. 4. These rolls are or may be of greater diameter than the rolls 58 and 59, and each stencil-frame 65 that they engage is therefore accelerated and drawn away from the following stencil-frames in the track. The stencil-frames, as

they are ejected from the tank are thrown upon suitable conveying-means, in spaced relation to each other, so that they may be thoroughly exposed for drying while *en route* to the stacking apparatus. A deflecting arm 73 is supported by a transverse bar 74, above the conveying-means, in position to deflect the stencil-frames onto said means, as they are ejected from the track by the rolls 67 and 68, see Fig. 4.

The conveying-means here shown comprises a belt 72, acting in conjunction with a belt 75, to convey the stencil-frames from the gluing-tank to the stacking-apparatus. As shown in Figs. 1, 3, and 8, the belts 72 and 75 are arranged in troughs comprising parallel side walls 76, and a floor board 77 connecting the same. Rolls 78 are provided for each belt at the end of the trough, and a tensioning-means is provided for the belt 72, adjacent the gluing-apparatus. This tensioning-means, see Fig. 1, comprises a roll 79, journaled between the free end of pivoted arms 80, having a counterweight 81. The belt 72 passes around this terminal roll 80 78, about the tension-roll 79, and then successively over driving-rolls 82, 83, 84, and 85, respectively mounted on shafts 86, 87, 88 and 89, journaled in parallel plates 189. The rotation of shaft 89, which is connected 90 to the motor or other power source by a chain 90, as will be hereinafter described, is translated to the shaft 88 through a pinion 91; to the shaft 87, by a pinion 92, which meshes with pinion 91; and to the shaft 86, by a pinion 93, which meshes with pinion 92. The belts 72 and 75 are driven at a faster speed than the speed of delivery of the stencil-frame thereto, so that the stencil-frames will be more or less widely spaced 95 apart thereon, thus admitting of the edges being exposed to enable them to quickly dry.

Referring jointly now to Figs. 1, 2, and 3, illustrating the completed machine: After the glued stencil-frames are passed onto the belt 72 by the ejecting-rolls 67 and 68, they are carried along to the end of the belt, and there dropped onto the belt 75, see Fig. 3. The belt 72 is of considerable length so that the upper faces of the stencil-frames are, in 110 their passage along the said belt, exposed for a period of time sufficient to thoroughly dry them. A curved chute 95, leads from the end of the belt 72, down onto the upper portion of the belt 75, see Fig. 3, and this chute serves to turn the stencil-frames over so that the face of the stencil-frame which was formerly in engagement with the belt 72 is uppermost when it falls upon belt 75, and is exposed to the atmosphere for drying. Belt 75 is also of sufficient length to insure 115 the drying of the exposed face of the stencil-frame, before it enters the stacking-apparatus to which the belt 75 leads. The belts are or may be intermediately supported 120 125 130

4
by transverse rolls 96, and the vertical bars 97 are or may be employed in maintaining the side walls 76 of the two belt-troughs in the proper spaced relation. One terminal roll 78 of the belt 75 is journaled, see Fig. 2, 5 upon a shaft 97 having a terminal sprocket-wheel 98, over which the chain 90 previously referred to operates. After passing about the rolls 78 the belt passes successively over driving-rolls 98, 99, 100, an idler-roll 101, about a tensioning-roll 102, and over a second idler 103, back over the transverse rolls 96. The rolls 98, 99, 100, are driven from the main drive-shaft 104, through the belt 105, which passes about a belt-wheel 106, secured to a stub-shaft 107, said shaft 107 connecting, by a smaller pinion 108, with the shaft 109 through the pinion 110 thereof. A pinion 111 on the other end of shaft 109, see Fig. 9, meshes with a pinion 112 on shaft 97, to thereby drive the roll 78 and the sprocket-wheel 98. The pinion 111 also meshes with a pinion 113 on shaft 114 of roll 99, thereby driving said roll, and the shaft 115 of roll 100 is driven through 20 its pinion 116 which meshes with pinion 113. The tensioning-roll 102 is journaled between the free ends of pivoted arms 117, having a weight 118 whereby the belt is maintained taut. The shafts 97, 109, 114, and 115 are 25 terminally journaled in parallel supporting-plates 119, which are mounted on the supporting-frame 120 and spaced above the top thereof, by suitable legs 121.

30 It will now be seen that the machine, as thus far described, makes provision for feeding the stencil-frames from a supply-holder along a track and into and out of a gluing-tank; and for ejecting the stencil-frames from said tank at an accelerated speed to 35 deliver them upon the first conveyer-belt 72; that one surface of each stencil-frame is allowed to dry while in transit on the upper conveyer-belt 72; that the stencil-frame is 40 then turned over as it falls upon the lower conveyer-belt 75; so that its other face will be exposed and allowed to dry before it passes into the stacking apparatus. This 45 stacking apparatus comprises essentially a vertical chute 122; a horizontal chute 123, see Fig. 11, and a receiving trough 124, which is horizontally disposed and arranged at right angles to the chute 123. The vertical chute 122, opens at its lower end into 50 the horizontal chute 123, and the bottom of said chute 123 comprises the upper portion of a horizontal belt 126, arranged for movement over a supporting board 127. Terminal-rolls 128 and 129, the latter of which is 55 driven by a means to be later described, are provided for said belt 126, and this belt is moved at a rate of speed sufficient to tilt or turn the stencil-frames, as they emerge from the vertical chute 122, and dispose them with 60 their longer edges horizontally arranged.

The side-walls 130 of the chute 123, see Fig. 9, are spaced a distance only slightly greater than the thickness of a stencil-frame so that these members are held in vertical position while passing through the chute 70 123. The top of the chute 123 is closed by plates 131, 132, which are hinged at 133, to afford ready access to the interior thereof in case stencil-frames become clogged therein, and to assist in directing the stencil-frames thereto. As each stencil-frame passes from the chute 123, into the end of the receiving-trough 124, its upper and lower edges are engaged by vertically spaced worms 134, 135, which are secured to shafts 136, 137, 75 80 arranged at right angles to the chute 123, and in line with the longitudinal center of the receiving-trough 124, see Figs. 9, 11. These worms act to move the stencil-frames forwardly into the receiving-trough. The 85 terminals of the worm-shafts 136 and 137 are connected by meshing pinions 138 and 139, and the shaft 136 is herein driven from the transverse-shaft 114 by engaging bevel-pinions 141, 142. It will be remembered that shaft 114 carries the roll 99, and is driven from the main power source by the belt 105. It is desired that each stencil-frame, as it passes from the chute 123 into the receiving-trough 124, be accelerated so 90 95 that it will be widely separated from the following stencil-frames, and the worms given sufficient time to move each stencil-frame out of the path of the next succeeding stencil-frame. For this purpose, there 100 are provided accelerating rolls 145 and 146, mounted on the upper end of vertical stub-shafts 147, 148, located on opposite sides of the belt 126, see Figs. 11 and 13. The rolls 145 and 146 engage the lower edge of the 105 110 stencil-frames and being positively driven at a rate of speed greater than the belt 126, they positively feed and also accelerate the movement of the stencil-frames and draw them away from the next succeeding stencil-frame, and positively project into position for engagement by the worm. To prevent clogging of the stencil-frames between the worms, I provide an arresting-device 115 which is periodically operated to retain and liberate at the proper time the foremost stencil-frame in the chute 123, to hold it against further movement therethrough, until the worm-shafts have made a complete rotation, which is sufficient to pass 120 any stencil-frame out of the path of the next succeeding stencil-frame. This arresting-device, see Figs. 9 and 12, comprises an L-shaped arm 149, pivoted in a bracket 150, and having a hook 151, which passes 125 through a slot 152, in the side wall 130, and into the path of that stencil-frame next to the stencil-frame which has just been engaged by the accelerating rolls 145 and 146. The hook 151 is normally held in arresting 130

position by a contractile spring 153, but is periodically swung into inoperative position, to allow another stencil to be moved forward into engagement with the rolls 145 and 146, 5 by a pitman 154, having an eccentric connection 155 with the worm shaft 136. Upon each rotation of the worm-shaft the pitman is moved outwardly to swing the arm 149, against the opposition of spring 153, to 10 therefore withdraw the hook 151 from the path of the stencil-frames in the chute 123. The belt 126 is driven from a pinion 139' of a worm shaft 137, see Fig. 12, through multiplying gears 156 and 157, the latter 15 being secured to the shaft of roll 129.

To relieve the strain on the worm-wheels and to assist them in moving the stencil-frames through the trough 124, there is provided a belt 159, arranged for movement 20 over transverse rolls 160 and 161, and suitably tensioned by an idler roll 162, see Fig. 10. The upper portion of this belt operates in a longitudinal opening 163, formed in the bottom of receiving trough 124, and is arranged 25 to receive the stencil-frames after they have been projected a short distance into the trough by the worms. This belt is driven from the shaft 114 by means of a belt 164, passing around the belt-wheels 165, 30 166, gears 167, 168, on the shafts 169, 170, and gears 171, 172, respectively, secured to shafts 169 and the shafts 173 of roll 161. The stencil-frames pass off of the belt 159 onto a pivoted bar 175, see Figs. 10 and 13. 35 This bar has a rectangular extension 176, which may be employed as a hand-grip for tilting the member 175, when a number of stencil-frames, sufficient to fill a box have been deposited thereon. The shaft 148 is 40 extended below the support 148' of the chute 123, and has at its lower end a belt wheel 180. A belt 181 connects the wheel 180 and a belt wheel 182 on shaft 114 and the rolls 145, 146 are thus driven from the shaft 114.

45 I claim:—

1. A machine of the character described, the combination of means for gluing blanks, means for feeding the blanks to said gluing-means, means for stacking the glued blanks, 50 and means for conveying the blanks from the gluing-means to the stacking-means, means associated with said conveying-means for turning over the blanks while *en route* to effect a thorough drying of both faces of the blanks.

2. A machine of the character described, the combination of a gluing-tank, means for feeding blanks into the tank, stacking-means for the glued blanks, a conveyer belt arranged 60 to receive the blanks as they emerge from the gluing-tank, another conveyer belt arranged to convey the blanks from the terminal of the first belt to the stacking-means, said belts being arranged one above the 65 other, and means for turning the blanks over

as they pass from one belt to the other whereby both faces of the blanks will be exposed to the atmosphere for a period of time to admit of drying while *en route* from the gluing-tank to the stacking-means. 70

3. A machine of the character described, the combination of means for gluing blanks, means for feeding the blanks to said gluing-means, means for stacking the glued blanks, means for conveying the blanks from the 75 gluing-means to the stacking-means, said means including complementary belts, and means for turning the blanks over as they pass from one belt onto the other, whereby the blanks are allowed to dry on both sides, 80 while *en route* from the gluing-means to the stacking-means.

4. A machine of the character described, the combination of means for gluing blanks, means for feeding the blanks to said gluing- 85 means, means for stacking the glued blanks, means for conveying the blanks from the gluing-means to the stacking-means, said conveying-means including complementary belts driven in opposite directions, and 90 means for turning the blanks over and for guiding them as they pass from one belt to the other.

5. A machine of the character described, the combination of means for gluing blanks, 95 means for feeding the blanks to said gluing-means, means for stacking the glued blanks, means for conveying the blanks from the gluing-means to the stacking-means, said conveying-means including superimposed 100 complementary belts having their corresponding ends located adjacent each other, and a curved chute leading from the upper belt to the lower belt for transferring the blanks from the upper belt to the lower belt and 105 for turning them over during such transfer.

6. A machine of the character described, the combination of a gluing-tank, a supply-holder adapted to contain a pile of blanks, a track leading from the said holder into and 110 out of the tank, feeding-mechanism for feeding the blanks *seriatim* from the supply-holder to the track, and for forcing them along the track in abutting relation, and supplemental feeding-mechanism for engaging 115 the blanks while arranged in the track for advancing them independently of the aforesaid means.

7. A machine of the character described, the combination of a gluing-tank, a supply- 120 holder adapted to contain a pile of blanks, a track leading from the supply-holder into and out of the tank, feeding mechanism for feeding the blanks *seriatim* from the supply-holder to the track, and for forcing the 125 blanks along the track in abutting relation, and supplemental feeding-mechanism for engaging the blanks supported by the track for advancing them independently of the aforesaid feeding-mechanism, said supple- 130

mental feeding-mechanism operating at a higher rate of speed than the aforesaid feeding-mechanism.

8. A machine of the character described, 5 the combination of a gluing-tank, a supply-holder adapted to contain a pile of blanks, a track leading from the said holder into and out of the tank, feeding-mechanism for feeding blanks from the supply-holder to the track, and a pair of accelerating feed-rolls arranged to engage the blanks while supported by the track.

9. A machine of the character described, 10 the combination of a gluing-tank, a supply-holder adapted to contain a pile of blanks, a track leading from the said holder into and out of the tank, feeding-mechanism for feeding the blanks from the supply-holder to the track, and for forcing them along the 15 track in abutting relation, and a pair of accelerating feed-rolls arranged to engage the blanks while supported by the track to advance them independently of the feeding-mechanism.

10. A machine of the character described, 20 the combination of a gluing-tank, a supply-holder adapted to contain a pile of blanks, a track leading from the said holder into and out of the tank, feeding-mechanism for feeding the blanks from said holder to the track and for forcing the blanks along the track in abutting relation, supplemental feed-rolls arranged to engage the blanks and feed them along independently of the feeding-mechanism, a conveyer belt adapted to 25 receive the blanks from the exit end of the tank, and a pair of accelerating rolls located at the said exit end of the tank for ejecting the blanks onto the belt at an accelerated rate of speed, said rolls being driven at a rate of speed greater than the speed of the supplementary feed-rolls, and the belts being moved at a faster speed than the speed of delivery of the stencil-frames 30 thereto, to thereby space the blanks from each other on the belt.

11. A machine of the character described, 35 the combination of a gluing-tank, a supply-holder adapted to contain a pile of blanks, a track leading from the said holder into and out of the tank, feeding-mechanism for feeding the blanks from the said holder to the track and for forcing them along the track in abutting relation, and a conveyer belt 40 adapted to receive the blanks at the exit end of the tank.

12. In a machine of the character described, 45 the combination of a gluing-tank, a supply-holder adapted to contain a pile of blanks, a track leading from the said holder into and out of the tank, feeding-mechanism for feeding the blanks from the said holder to the track and for forcing them along the track in abutting relation, and a conveyer belt adapted to receive the 50

blanks at the exit end of the tank, said belt being movable faster than the speed of delivery of the blanks thereto, thereby to provide for disposing them in spaced relation thereupon.

13. A machine of the character described, 55 the combination of a gluing tank, a supply-holder adapted to contain a pile of blanks, a track leading from the said holder into and out of the tank, feeding-mechanism for feeding the blanks from the said holder to the track, and for forcing them along the track in abutting relation, a conveyer-belt adapted to receive the blanks from the exit end of the tank, and accelerating means located at 60 the exit end of the tank for accelerating the speed of the blanks as they emerge from the tank and for disposing them in spaced relation upon the belt.

14. In a machine of the character described, 65 the combination of a gluing-tank, a supply-holder adapted to contain a pile of blanks, a track leading from the said holder into and out of the tank, feeding-mechanism for feeding the blanks from the said holder to the track and for forcing them along the track in abutting relation, a continuously movable conveyer belt adapted to receive the blanks at the exit end of the tank, and a pair of rolls for engaging the 70 blanks at such place, and for squeezing them to remove the surplus glue and for disposing them in spaced relation upon the belt.

15. A machine of the character described, 75 the combination of a gluing-tank, a feeding-mechanism for supplying blanks to the tank, a track leading into and out of the tank and along which the blanks are moved, and accelerating feed-rolls arranged to engage the blanks while supported by the track and 80 for drawing each blank away from the following blank.

16. A machine of the character described, 85 the combination of a gluing-tank, a track leading into and out of the tank, and feeding-mechanism for forcing the blanks along the track in abutting relation, and accelerating-means arranged to engage the blanks while supported by the track and to draw 90 each blank away from the following blanks 95 in the track, to thus advance them.

17. A machine of the character described, 100 the combination of a gluing-tank, a track leading into and out of the tank, feeding-mechanism for forcing blanks along the track in abutting relation, a conveyer belt adapted to receive the blanks from the exit end of the tank, an accelerating-means located at the exit end of the tank for accelerating the speed of the blanks as they 105 emerge from the tank and for disposing them in spaced relation upon the belt.

18. An apparatus for stacking blanks, 110 including a vertical chute into which the blanks are fed, a horizontal chute receiving 115

the blanks from the lower end of the vertical chute, means for conveying the blanks through the horizontal chute, a receiving trough in which the blanks are stacked on 5 edge, and means for conveying the blanks from the end of the horizontal chute into the receiving trough.

19. An apparatus for stacking blanks, including a vertical chute into which the 10 blanks are fed and down which they fall, a horizontal chute into which the blanks pass from the vertical chute, means for turning the blanks as they enter the horizontal chute, whereby the blanks are disposed in 15 vertical position to rest on their longitudinal edges, said means also acting to convey the blanks through the horizontal chute, a receiving-trough at right angles to the horizontal chute, and means for transferring the 20 blanks from the horizontal chute into the receiving-trough,

20. An apparatus for stacking blanks, including a vertical chute down into which blanks are fed and down which they fall, a 25 horizontal chute into which the blanks pass from the vertical chute, means for turning the blanks as they enter the horizontal chute whereby the blanks are disposed in vertical position to rest on their longitudinal edges, 30 said means also acting to convey the blanks through the horizontal chute, a receiving-trough at right angles to the horizontal chute, means for transferring the blanks from the horizontal chute into the receiving-trough, and means operating in the receiving-trough for conveying the blanks toward the outer end thereof.

21. An apparatus for stacking blanks, including a vertical chute into which the 40 blanks are fed, a horizontal chute receiving the blanks from the lower end of the vertical chute, a receiving trough at right angles to the horizontal chute and in which the blanks are adapted to be stacked in vertical position, a belt which forms the bottom of the 45 horizontal chute and moves at a rate of speed greater than the speed of the blanks as they pass down the vertical chute whereby the blanks are turned to rest in vertical 50 position on the longitudinal edges, and are conveyed through the horizontal chute.

22. An apparatus for stacking blanks, including a vertical chute into which the blanks are fed, a horizontal chute receiving 55 the blanks from the lower end of the vertical chute, a receiving-trough at right angles to the horizontal chute and in which the blanks are adapted to be stacked in vertical position, a belt which forms the bottom of 60 the horizontal chute and moves at a rate of speed greater than the blanks as they pass down the vertical chute, whereby the blanks are turned to rest in vertical position on the longitudinal edges, and are conveyed 65 through the horizontal chute, and a pair of

parallel, vertically-spaced worms having their axes of rotation at right angles to the horizontal chute for engaging the blanks as they pass into the receiving trough and feeding them forwardly into said trough. 70

23. A stacking apparatus including a vertical chute into which the blanks are fed, a horizontal chute receiving the blanks from the lower end of the vertical chute, a receiving trough at right angles to the horizontal chute, a conveyer belt for conveying the blanks through the horizontal chute, and a pair of worms having their axes in rotation at right angles to the horizontal chute, said worms being engageable with the blanks for 75 transferring them from the horizontal chute into the receiving trough.

24. A stacking apparatus including a vertical chute into which the blanks are fed, a horizontal chute receiving the blanks from 80 the lower end of the vertical chute, a receiving trough at right angles to the horizontal chute, a conveyer belt for conveying the blanks through the horizontal chute, and a pair of worms having their axes in rotation 85 at right angles to the horizontal chute, said worms being engageable with the blanks for transferring them from the horizontal chute into the receiving trough, and a conveyer belt in the receiving trough arranged to receive the blanks after they have been fed from said trough a short distance by the worms. 90

25. A stacking apparatus including a horizontal chute, a receiving trough at 100 right angles thereto, and arranged at one end thereof, a conveyer belt for conveying blanks through the horizontal trough, means at the junction of the chute and trough for transferring the blanks from the chute to the 105 trough.

26. A stacking apparatus including a horizontal chute, a receiving trough at right angles thereto, and arranged at one end thereof, a conveyer belt for conveying blanks 110 through the horizontal trough, means at the junction of the chute and trough for transferring the blanks from the chute to the trough, and a conveyer belt in the trough arranged to receive the blanks after they have 115 been fed a short distance into the trough by the worms for moving the blanks toward the outer end of the trough.

27. A stacking apparatus including a horizontal chute, a receiving trough at right 120 angles thereto, and arranged at one end thereof, a conveyer belt for conveying blanks through the horizontal trough, means at the junction of the chute and trough for transferring the blanks from the chute to the 125 trough, and accelerating means located adjacent the worms for accelerating the speed of each blank immediately prior to its engagement by the worms whereby each blank is thrown away from the following blanks 130

in the horizontal chute prior to its engagement by the worms.

28. A stacking apparatus including a horizontal chute, a receiving trough at right angles thereto, and arranged at one end thereof, a conveyer belt for conveying blanks through the horizontal trough, means at the junction of the chute and trough for transferring the blanks from the chute to the trough, and an arresting member operable for periodically arresting the movement of the blanks through the horizontal chute.

29. A stacking apparatus including a horizontal chute, a receiving trough at right angles thereto, and arranged at one end thereof, a conveyer belt for conveying blanks through the horizontal trough, means at the junction of the chute and trough for transferring the blanks from the chute to the trough, and an arresting member operable for periodically arresting the movement of the blanks through the horizontal chute, and means for periodically projecting the arresting member into operative position 25 and retracting it into inoperative position.

30. The blank-holder and table on which it rests, said table having a curved guide-passage extended beneath the holder adapted to receive the lowermost blank of the pile, 30 the holder being arranged tangential to said passage, and means for engaging the lowermost blank and moving it along said curved guide-passage in a curvilinear direction, thus removing it from the bottom of the pile, and 35 turning it in a horizontal plane during such movement.

31. The blank-holder and table on which it rests, said table having a curved guide-passage extended beneath the holder adapted to receive the lowermost blank of the pile, 40 the holder being arranged tangential to said passage, an oscillating feeding-means having its engaging-portion movable in said curved passage and arranged to engage the lowermost blank and move it along said passage in a curvilinear direction, thus removing it from the bottom of the pile, and turning it 45 in a horizontal plane during such movement.

32. A table having a curved guide-passage, 50 a blank-holder arranged thereon substantially tangential to said passage, whereby the lowermost blank of the pile contained in said holder is adapted to enter said passage, and means movable in said passage to successively engage the lowermost blanks of the pile and move them along the passage in a

curvilinear direction, and remove them from the bottom of the pile and turn them in a horizontal plane while so moving them.

33. A table having a curved guide-passage, 60 a blank-holder arranged thereon substantially tangential to said passage, whereby the lowermost blank of the pile contained in said holder is adapted to enter said passage, and an oscillating member having an engaging-portion movable in said passage and arranged to engage the lowermost blank of the pile and move it along the passage in a curvilinear direction, thus removing it from the bottom of the pile, and turning it in a 70 horizontal plane while so moving it.

34. A table having a curved guide-passage, a blank-holder arranged thereon substantially tangential to said passage, whereby the lowermost blank of the pile contained in 75 said holder may enter said passage, an oscillating member having an end-portion formed with a forwardly extended tongue and a shoulder, the tongue adapted to extend beneath the pile of blanks and the shoulder 80 to engage the edge of the lowermost blank of the pile, said end-portion being movable along said passage to remove a blank from the bottom of the pile.

35. A table having a curved guide-passage, 85 a blank-holder arranged thereon substantially tangential to said passage, whereby the lowermost blank of the pile contained in said holder is adapted to enter said passage, and means movable in said passage to successively engage the lowermost blanks of the pile and move them along the passage in a 90 curvilinear direction, and remove them from the bottom of the pile and turn them in a horizontal plane, while so moving them, a 95 track comprising two grooved bars arranged in parallel relation, in continuation of said guide-passage, and a pair of positively driven feeding-rolls, near the junction of the track and guide-passage, to engage the stencil-frames projected from the holder and positively thrust them into the track, to be engaged by the grooved bars thereof and moved into parallel relation therewith.

In testimony whereof, I have signed my 105 name to this specification, in the presence of two subscribing witnesses.

STERLING ELLIOTT.
